UNITED STATES PATENT OFFICE.

MARTIN KNUDSTRUP, OF ST. CLAIR, MICHIGAN.

STEAM TRAP.

Application filed September 14, 1925. Serial No. 56,363.

This invention relates to steam traps and particularly to devices of this character designed for use in steam systems, oil separators, condensers and vacuum systems to collect the water of condensation from the system, and to periodically return the water under pressure to the boiler, or other point of delivery.

The invention has also among its objects 10 to simplify, render more efficient, and improve generally devices of this character, and these as well as other objects, advantages, and novel details of construction, will be made more apparent as this description 15 proceeds, especially when considered in connection with the accompanying drawings, wherein one illustrative embodiment of the invention is shown, and wherein

Fig. 1 is a side elevation of a steam trap 20 constructed in accordance with this invention,

Fig. 2 is a sectional end elevation with certain parts eliminated for the sake of clearness, and

Fig. 3 is a top plan view.

Referring now particularly to the drawings wherein like reference characters indicate like parts, it will be noted that there is illustrated a tank 9 within which there 30 is arranged a float 10 provided with springs 11 for cushioning the float when it engages the sides of the tank. This float is connected by means of a rod 12 to a shaft 13 extending transversely of the tank 9 at one end 35 thereof. The shaft is rotatably journaled in the end of the tank and extends outwardly through the walls thereof and through stuffing boxes 14. One extended end of shaft 13 is journaled in arm 15, and to this end 40 of shaft 13 there is connected for rotation therewith an arm 16.

Arranged at one side of tank 9 is a supporting platform 17 secured in place preferably by means of brackets 18. Carried upon this supporting platform is a plurality of guide members 19 and reciprocably mounted in these guides 19 is a reciprocating member 20. This reciprocating member comprises a rounded rod portion 21 upon which a sleeve member 22 is slidably arranged, this sleeve being pivotally connected as at 23 by means of a link 24 to arm 16. The movement of sleeve 22 on rod 21 is opposed in both directions by means of springs 25 and 55 26 which surround rod 21 and engage sleeve 22 at both ends thereof and bear with their

other ends against collars 27 adjustably fixed on the rod 21 by means of set screws 28.

The section 29 of the reciprocal member 20 is formed with a plurality, here shown as 60 two, depressions or recesses 30 and 31 spaced longitudinally of the reciprocal member as clearly shown in Fig. 1. The section 29 is also formed, adjacent depressions 30 and 31, with shoulders or abutments 29'. A pin 32 65 carried by an arm 33 pivoted as at 34 to an upright 35, is adapted to abut shoulders 29' and enter either of the depressions 30 or 31 upon a shifting of the reciprocal member 20 to either of its positions. The arm 33 is normally urged into a position in which the pin 32 rests in either of the depressions 30 or 31 by means of a weight 36 carried by the end of this arm. 70

The reciprocal member 20 is pivotally connected as at 37 to a link 38, which in turn is connected to a link 39 pivotally connected as at 40 to the operating arms 41 of valves 42 and 43 arranged respectively in the steam inlet and steam vent pipes 44 and 45. The 80 condensate inlet pipe is indicated by the reference character 46, the condensate escaping from the trap through outlet pipe 47. Check valves 48 arranged in these condensate intake and discharge lines permit an 85 accumulation in the tank of the condensate, in the customary manner.

In operation, if the tank 9 contains no condensate the float 10 will be substantially in the position illustrated in Fig. 1, in which 90 position the valve 43 in the steam vent line 45 is opened while the valve 42 in the steam intake line is closed. When condensate accumulates in tank 9 by entering through condensate intake line 46, float 10 will rise, 95 this movement rotating shaft 13 and consequently rocking arm 16, which through the medium of link 24 moves sleeve 22 longitudinally along the section 21 of the reciprocating member 20 in a direction to compress 100 spring 25. When spring 25 has been compressed to its limit reciprocable member 20 will be moved to the left, as seen in Fig. 1, the pin 32 on weighted arm 33 moving out of the rounded depression 30 and dropping 105 into depression 31. This movement of reciprocable member 20, through the medium of links 38 and 39, simultaneously operates valves 42 and 43, whereby valve 42 in the steam inlet line is opened while valve 43 in 110 the steam outlet line is closed.

Steam is thus admitted to tank 9 where-

- 2 upon a steam pressure is accumulated on the top surface of the condensate in the tank 9, causing it to pass out through the check valve 48 in the condensate discharge line 47.
- 5 When the accumulated condensate has all been discharged float 10 will again assume the position illustrated in Fig. 1, whereupon spring 26 will be compressed by the movement of sleeve 22 to shift reciprocable member 20 to the right, as seen in Fig. 1, whereupon pin 32 will be caused to again repose in depression 30. As the condensate again accumulates in tank 9 the cycle of operations just described will be repeated.
- 10 The springs 11 associated with the float 10 form a cushioning means to minimize any shocks to the apparatus caused by the engagement of the float with the sides of tank 9. The weighted arm 33 carrying locking pin 32 cooperates with the depressions in reciprocable member 20 to hold this member in either of its positions while the movement of float 10 is accumulating sufficient power in either of springs 25 or 26 to shift the reciprocable member. The movement of reciprocable member 20 as limited and controlled by locking pin 32, is sufficient, through the medium of links 38 and 39, to fully move valves 42 and 43 from open and closed position to closed and open position respectively and vice versa. Consequently, liability of the valves being insufficiently operated and remaining at intermediate positions is eliminated. By providing the adjustable collars 27 with set screws 28 the point at which reciprocable member 20 will be shifted may be governed by regulating the tension on springs 25 and 26.
- 15 The apparatus herein described not only affords an efficient means for periodically forcibly expelling the accumulations of condensate but accomplishes this in a simple and efficient manner. The operative mechanism of the device is conveniently accessible, adjustable and easily assembled, and eliminates the use of trunnions.
- 20 While one embodiment of the invention has been described and illustrated somewhat in detail, it will be immediately apparent that various modifications may be resorted to without departing from the spirit and scope of this invention, and to this end reservation is made to make such changes as may come within the purview of the accompanying claims.
- 25 What I claim as my invention is:
1. In a steam trap, a tank provided with a condensate inlet and outlet, valved steam inlet and outlet pipes, a float in said tank responsive to the rise and fall of the condensate accumulated therein, means including a reciprocable member connecting said float to said valves for operating the latter, said member being formed with longitudinally spaced recesses adjacent one end and a gravity actuated latch member, engageable in said recesses for arresting and locking said reciprocable member.
2. In a steam trap, a tank provided with a condensate inlet and outlet, valved steam inlet and outlet pipes, a float in said tank responsive to the rise and fall of the condensate accumulated therein, means including a reciprocable member connecting said float to said valves for operating the latter, said reciprocable member being formed with spaced shoulders with adjacent recesses, and a weighted arm provided with a pin engageable with said shoulders and recesses for arresting and locking said reciprocable member.
3. In a steam trap, a tank provided with a condensate inlet and outlet, valved steam inlet and outlet pipes, a float in said tank responsive to the rise and fall of the condensate accumulated therein, means including a member reciprocable longitudinally of said tank and connecting said float to said valves for operating the latter, power accumulating means for reciprocating said reciprocable member, and a gravity latch engageable with said reciprocable member for arresting and locking the same.
4. In a steam trap, a tank provided with a condensate inlet and outlet, valved steam inlet and vent pipes, a float responsive to the rise and fall of the condensate in said tank, a reciprocable member, a sleeve slidable on said member, means connecting said sleeve to said float for reciprocating the former, power accumulating springs resisting the movement of said sleeve, means connecting said reciprocable member to said valves for operating the latter, and a latch mechanism for arresting and locking said reciprocable member in its positions of rest.
5. In a steam trap, a tank provided with a condensate inlet and outlet, valved steam inlet and outlet pipes, a float in said tank responsive to the rise and fall of the condensate accumulated therein, means including a member mounted exteriorly of said tank and reciprocable longitudinally thereof for connecting said float to said valves and for operating the latter, and gravity actuated means engageable in recesses formed in said reciprocable member for arresting and locking the latter in its positions of rest.
- In testimony whereof I affix my signature.
